(57) **CLAIM**

The ornamental design for a clutch purse as shown and described.

DESCRIPTION

FIG. 1 is a first top perspective view of a clutch purse in an open configuration.

FIG. 2 is a second top perspective view thereof.

FIG. 3 is a side perspective view thereof.

FIG. 4 is a front perspective view thereof.

FIG. 5 is a side perspective view of the clutch purse in a closed configuration; and,

FIG. 6 is a side plan view of the clutch purse in an open configuration, the opposite side being a mirror image thereof.

In the drawings, the broken lines showing a mobile phone illustrate the environment in which the clutch purse is used and forms no part of the claimed design.
